Inventor
George O. Bergstrom
By Attorney G. H. Abel

UNITED STATES PATENT OFFICE.

GEORGE O. BERGSTROM, OF NEENAH, WISCONSIN, ASSIGNOR TO BERGSTROM BROTHERS & CO., OF SAME PLACE.

DESIGN FOR A HEATING-STOVE.

SPECIFICATION forming part of Design No. 23,911, dated December 25, 1894.

Application filed August 6, 1894. Serial No. 519,604. Term of patent 7 years.

To all whom it may concern:

Be it known that I, GEORGE O. BERGSTROM, a citizen of the United States, residing at Neenah, in the county of Winnebago and State of Wisconsin, have invented a new and original Design for a Heating-Stove set forth in the accompanying drawing of a stove having said design, which is made a part of this specification.

My invention comprises a certain new and original design for the various castings of a heating stove, as follows: One of these novel features is a design for the stove leg base, 1, consisting of a four sided base having at the corner thereof, longitudinally curved legs ornamented with corresponding scrolls *a*, at their side edges, the horizontally disposed beads *b*, between said scrolls, the scroll *a'*, and the series of scrolls *a''*, diminishing in area toward the middle of each side of said base.

The second part of my invention includes the stove base section 2, having the upper border *c*, of vertical fluting, the plain beveled lower border *c'*, the corner pillars *d*, ornamented with a base, capital and a spirally beaded shaft, the stove base side panel *e*, inclosed by the two plain border moldings *e'*, and ornamented with the arabesque scroll work *f*.

The third part of my invention includes the design for the ash pit door 3, ornamented with the scroll *g*, overlying the series of vertical perforations *g'*.

The fourth part of my invention includes the design for the foot rail, (its front and one side being shown,) and consisting of the rail 4, having an outward and slightly downward curved surface with rounded corners *4'*, ornamented upon their upper surface with a scroll *h*, the front edge of said rail being curved inward and its upper surface ornamented with the scrolls *h'*, and its side edges being an irregular curve with its upper surface ornamented with the scrolls *h''*.

The fifth part of my invention comprises the flue wings 5, having outward curved lower ends and a convex outer surface embellished with a series of scrolls *i*.

The sixth part of my invention includes the front body 6 of the stove design, having the upper side border ornaments *j*, the inter-

mediate side border ornaments *j'*, the upper panel border scrolls *k*, *k'* and *k''*, and two ornamental panels, 7 and 10, ornamenting 55 said front near its upper and lower parts.

The seventh part of my invention includes the design for the panel 7, ornamented with the arabesque scroll work 1, inclosing the elliptical ornament 1'.

The eighth part of my invention includes the design of the door 8, ornamented with the scroll *m*.

The ninth part of my invention includes the design of the door 9, embellished with the 65 French Gothic perforations *n*, the ornaments *n'*, each side of said perforations, and below them the scroll *o*.

The tenth part of my invention includes the design of the panel 10, inclosing centrally thereof a circular raised tablet having a plain border *p*, with a single scroll *p'*, branching from opposite sides thereof and the scrolls *q*, branching from the lower side of said tablet toward and covering the right and 75 left hand ends of said panel.

The eleventh part of my invention comprises the stove top section 11, having for its design a plain convex border *r*, the convex molding *s* underneath said border ornamented with the fine scroll work *s'*, and above said border the convex top *t*, of said section ornamented with the scroll work *t'*.

The twelfth part of my invention includes the design of the swinging top piece 12, having the plain lower border *u*, the inward inclined fluting *v*, surmounted by the border bead *u'*, and the convex top *w* of said top piece, ornamented with the scrolls *w'*.

The thirteenth part of my invention includes the design for the tea kettle attachment 13, having a flue with a convex lower portion *x*, surmounted by a plain border *y*, said lower portion being ornamented with depending ornaments of different lengths, *z*, *z'*, 95 those around the rear part of said flue being alternately long and short.

The fourteenth part of my invention consists in combining all of the above described shapes and ornaments in the castings of a 100 heating stove.

The rear body of the stove, the tablet in the panel 10, and the urn surmounting the stove, are no part of my present invention.

Having described my invention, what I claim, and desire to secure by Letters Patent, is—

1. In a design for a stove the design for the stove leg base 1, substantially as shown and described.
2. In a design for a stove the design for the stove base section 2, substantially as shown and described.
3. In a design for a stove the design for the ash pit door 3, substantially as shown and described.
4. In a design for a stove the design for the foot rail 4, substantially as shown and described.
5. In a design for a stove the design for the flue wings 5, substantially as shown and described.
6. In a design for a stove the design for the front body of the stove, 6, substantially as shown and described.
7. In a design for a stove the design for the panel 7, substantially as shown and described.
8. In a design for a stove the design for the door 8, substantially as shown and described. 25
9. In a design for a stove the design for the door 9, substantially as shown and described.
10. In a design for a stove the design for the panel 10, substantially as shown and described.
11. In a design for a stove the design for the stove top section, 11, substantially as shown and described.
12. In a design for a stove the design for the top piece, 12, substantially as shown and described. 35
13. In a design for a stove the design for the tea kettle attachment, 13, substantially as shown and described.
14. The design for a heating stove, as herein shown and described. 40

GEORGE O. BERGSTROM.
